Primary Examiner — Jonathan J Han(74) Attorney, Agent, or Firm — Banner & Witcoff, Ltd.(57) CLAIM

The ornamental design for a shoe as shown and described.

DESCRIPTION

FIG. 1 is a side view of a shoe showing my new design; FIG. 2 is a rear perspective view thereof; and, FIG. 3 is a front perspective view thereof.

The broken lines on the strap element immediately adjacent to the shaded area define the bounds of the claimed design and form no part thereof. The unshaded, broken line rounded trapezoidal shape within the shaded area forms no part of the claimed design. The broken lines depicting the remainder of the shoe form no part of the claimed design.
